UNITED STATES PATENT OFFICE.

WILLIAM DUECHTING, OF CHICAGO, ILLINOIS.

REFRIGERATOR-CAR.

SPECIFICATION forming part of Letters Patent No. 425,599, dated April 15, 1890.

Application filed February 10, 1890; Serial No. 339,802. (No model.)

To all whom it may concern:

Be it known that I, WILLIAM DUECHTING, of Chicago, in the county of Cook and State of Illinois, have invented certain new and useful Improvements in Refrigerator-Cars; and I do hereby declare that the following is a full, clear, and exact description thereof, reference being had to the accompanying drawings, and to the letters of reference marked thereon, which form a part of this specification.

This invention relates to refrigerating apparatus applied to railway-cars, and has for one of its objects to provide a construction by which bodies of ice may be formed in the car instead of being placed therein after their formation elsewhere.

The invention also has for one of its objects to provide an arrangement of a series of pans one above another within a partial inclosure, whereby air may circulate downwardly over and under the several pans in a zigzag course, and thus become more effectively cooled.

Another object of the invention is to provide a construction whereby an upper pan when filled to the proper depth will overflow into a subjacent pan, and thus the entire series of pans may be filled by delivering water into the upper one.

The invention has for still another of its objects to provide a construction whereby cold air may be driven forcibly in a horizontal direction as it leaves the cooling-chamber.

In the accompanying drawings, which illustrate one form in which my invention may be constructed, Figure 1 is a central vertical longitudinal section of a car provided with my improved apparatus. Fig. 2 is a horizontal section in the line 2 2 of Fig. 1. Fig. 3 is a vertical transverse section in the indirect line 3 3 of Fig. 2.

A represents a car, of which a is the floor, a' the roof, and a² the end.

B is an inclosure, here shown as extending across one end of the car and open at both the top and bottom to permit a downward movement of air through the same.

C C are a series of horizontal pans supported one over another by ribs c c or otherwise within the inclosure B. Each pan C is provided with one or more holes in its bottom, each surrounded by a vertical tube c',

extending to such height within the pan as it may be desired to fill the same with water preparatory to freezing the latter. The tubes c' of one pan are arranged out of line with the corresponding tubes of the subjacent pan, so that when water is poured into the uppermost of said pans it will fill the latter to the height of the tubes c' thereof and then overflow through said tubes into the subjacent pan, so that in this manner all the pans may be filled from above to a required depth. The lowermost pan is provided with an overflow-pipe c², which leads outside the car, as indicated in Fig. 3, said pipe being provided externally to the car with a cock c³, by which, when the pans shall have been filled, said overflow-pipe may be closed.

C' represents a spout leading through the side of the car above the uppermost pan C and adapted to connect outside the car with a hose, by which water may be sent to the pans C C from any suitable source of supply.

D is a brine-chamber adjacent to the pan-chamber or inclosure B. In the present drawings said brine-chamber D is shown located adjacent to the wall of the car and between it and the pan-chamber B; but obviously it may, if desired, be extended around the pan-chamber or otherwise appropriately disposed with reference thereto.

E represents a pipe coiled within the brine-chamber, said pipe being prolonged outside the car at each end and provided with a valve at each protruding end, as shown at E', Fig. 1. It is intended that the pipe E of one car may be temporarily coupled with the corresponding pipe of the adjacent car and connected with a stationary ammonia-pump located adjacent to the track on which the cars stand, and by the circulation of ammonia in a state of expansion after compression through the pipe and coil E in the usual manner the temperature of the brine within the chamber D will be lowered to such an extent as to congeal the water in the pans C, thus forming a series of thin blocks of ice in said pans.

For the circulation of the air within the car in contact with the ice in the pans C C, any suitable form of openings out of line with each other through or at the ends or sides of said pans may be provided. In the present case the openings through the tubes c' are

utilized for that purpose, and the zigzag course of the descending air through the pan-chamber B is illustrated by arrows. After the brine in the chamber D has been reduced to the proper temperature the valves E' in the pipe E are closed and the pipes of one car desirably uncoupled from those of another. The congelation of the water in the pans will be rapid and the blocks of ice completely formed before the car will be put in motion.

F is a hood applied to the open bottom of the inclosure or pan-chamber B, the front vertical portion of said hood having an opening f, preferably in the middle thereof, through which a relatively narrow stream of air will pass from the pan-chamber with greater rapidity, and therefore to a greater distance than if the opening were of the full width of the car. Several openings f may be provided in the hood, if desired, their size being determined with reference to the force or velocity desired to be given to the air-streams.

I claim as my invention—

1. The combination, with a car, of a brine-chamber containing a coil for the passage of ammonia, an inclosure adjacent to the brine-

chamber and open at top and bottom for the admission and discharge of air, and a series of pans arranged within said inclosure, one above another, and with a space between them, passages being provided by which air may descend from the top to the bottom of the inclosure and horizontally between the pans, substantially as described.

2. The combination of the brine-chamber D, containing a coil E, the contiguous pan-chamber B, open at top and bottom, and a series of pans C, provided with tubes c', arranged out of line with each other, substantially as described, and for the purposes set forth.

3. In combination with the pan-chamber B, a hood F, covering the open bottom of the pan-chamber and provided with a contracted opening f in its front portion.

In testimony that I claim the foregoing as my invention I affix my signature in presence of two witnesses.

WILLIAM DUECHTING.
